METHOD OF HEATING

Clayton A. Dunham and Aubra R. Dunham, Glencoe, Ill., assignors to Experimental Laboratories Incorporated, Chicago, Ill., a corporation of Illinois

Application July 8, 1929, Serial No. 376,537

15 Claims. (Cl. 237—12)

This invention relates to a new and improved method of heating in which a heating medium consisting of mixed steam and products of combustion is produced in a generator of the internal combustion type and transmitted to and through the radiators.

According to this invention the entire system is operated under a partial vacuum, or a sub-atmospheric pressure, produced by a temperature controlled fan or other suction means connected with the outlets of the radiators. This exhausting mechanism not only draws out and expels to the outer atmosphere the non-condensable gases after they have given up most of their heat in the radiators and in the preceding process of generating steam, but also maintains a sub-atmospheric pressure in both the radiating system and in the generator. Steam condensed in the radiating system is returned by gravity to the generator for reconversion into steam. The vacuum produced in the generator serves not only to draw in air from the outer atmosphere for combustion purposes but regulates the admission of the gas or other fuel in accordance with the degree of vacuum existing in the generator, which in turn is regulated by the temperature in the enclosure to be heated and by the number of radiators or the volume of condensing space in service. The entire system within the building to be heated is closed, and since the system is operated under sub-atmospheric pressure if any leakage does occur it will be of air into the system rather than the escape of steam or combustion gases therefrom.

The principal object of this invention is to provide an improved method of heating of the type briefly described hereinabove and disclosed more in detail in the specifications which follow.

40 Another object is to provide a method of heating which utilizes a boiler of the internal combustion type operating under sub-atmospheric pressures.

Another object is to provide a method of heating designed to prevent possible leaks of gas into the building.

Another object is to provide a method in which the fuel burned and the combustion air admitted is regulated by the radiator control, that is when 50 additional radiating space is added the combustion will be automatically increased to provide additional heating medium.

Another object is to provide a simple, inexpensive and efficient method of heating small structures, which will give a maximum of con-

venience and comfort at a minimum of care and cost.

Other objects and advantages of this system will be more apparent from the following detailed description of one approved form of apparatus adapted for carrying out the principles of this invention. 5

In the accompanying drawing:

Fig. 1 is a diagrammatic elevation, partially in vertical section, showing the principal elements of the heating system. 10

Fig. 2 is a vertical section through the automatic fuel control valve.

Fig. 3 is an elevation, partially in vertical section, of one of the radiator inlet valves.

The main features of the apparatus are a generator A for the heating medium, a radiating system comprising a plurality of radiating units B, an exhausting mechanism C, and an automatic fuel control valve D.

The generator A may take a variety of forms, one of its essential characteristics being that it is entirely closed except for the inlets for water, fuel and combustion air, and the outlet for the heating medium, none of these having any direct communication with the atmosphere within the building whereby a sub-atmospheric pressure may be maintained within the generator and the escape of fluids therefrom is prevented. The generator may be made of metal or suitable refractory materials, or both. In the form here shown somewhat diagrammatically by way of example, the outer casing comprises a bottom wall 1, vertical cylindrical side walls 2, and a dome shaped roof or cover 3 from which leads the supply pipe 4 for conducting the heating medium to the radiating system. The main inner container or boiler unit consisting of a bottom wall 5 and inner and outer cylindrical walls 6 and 7 forms an annular container or basin for the main supply of water indicated at 8. A pan 9 open at its upper side and comprising an upwardly dished bottom wall 10 and downwardly converging side walls 11 is supported on the top of the inner cylindrical wall 6. The water supply pipe 12 extends inwardly through the outer casing and has a downwardly projecting discharge leg 13 extending beneath the water level in pan 9 so as to form a water seal. The air inlet tube 14 projects upwardly through the bottom walls 1 and 5 and 50 extends centrally upward within the lower portion of the inner annular wall 6 so as to form a third water container or reservoir 15 of annular form. The air inlet pipe 16 leads in through one wall 17 of the building from the outer atmos- 55

phere and connects through fitting 18 with the lower end of the air inlet tube 14. The supply pipe 19 for gas or other fuel extends inwardly through a closure plug 20 in one end of fitting 18 and terminates in a burner nozzle 21 of suitable form near the upper end of air supply tube 14. The space 22 within the upper portion of cylinder 6 constitutes the main combustion chamber, the flame being indicated at 23. Any suitable means may be utilized to ignite the fuel. An opening closed by a removable plug 60 may be provided in the outer casing 2, through which opening a lighted taper or an electric-sparking device can be inserted to initially ignite the gas, after which plug 60 is replaced to seal the opening. A plurality of circular series of openings 24 and 25 are formed in the cylindrical wall 6 to permit the products of combustion to pass from chamber 22 into the main chamber within the outer casing. The lower openings 25 also determine the water level in the outer reservoir 8. A water discharge pipe 26 leads from a fitting 27 in the air inlet pipe 16, pipe 26 being looped upwardly at 28 to provide a water seal against the entrance or escape of gases through this pipe.

The gas supply pipe 29 leads from the outside source of gas supply to the valve chamber 30 of the automatic control valve D, the supply pipe 19 leading from this valve chamber to the burner 21. One suitable form of control valve D is indicated diagrammatically in Fig. 2. A valve plate 31 is adapted to engage with the valve seat 32 to cut off the flow of gas or other fuel through the valve. Valve stem 33 leads upwardly from valve plate 31 to a flexible diaphragm 34 housed in a diaphragm casing 35. The chamber 36 beneath the diaphragm 34 is open to atmospheric pressure through aperture 37. The chamber 38 above diaphragm 34 is connected through pipe 39 with the interior of generator A, whereby diaphragm chamber 38 will always be under substantially the pressure existing in the generator. A sealing diaphragm 40 of the flexible bellows type is connected between the valve casing 30 and the valve plate 31 to prevent the escape of gas around valve stem 33 in the upper portion of the valve casing.

When the chambers 36 and 38 at the two sides of diaphragm 34 are both under atmospheric pressure and diaphragm 34 is in its normal central position the valve plate 31 will be held against valve seat 32 to close the valve. If desired an auxiliary spring 41 may be employed for holding the valve against its seat. When the pressure within the generator A is lowered below atmospheric pressure, the pressure in chamber 38 above diaphragm 34 will be correspondingly lowered and the atmospheric pressure within chamber 36 beneath the diaphragm will lift the valve so as to permit gas to flow from pipe 29 to pipe 19 and thence to burner 21. The greater the vacuum within the generator, the lower the pressure above diaphragm 34 and consequently the greater pressure differential will be exerted on this diaphragm to open the valve so that the supply of gas admitted to burner 21 will be increased proportionately as the pressure is lowered within the generator. A very small pipe 61, provided with a normally open stop-cock 62, is shunted around valve D to connect gas supply pipe 29 with gas pipe 19 so that a small flow of gas to the burner 21 will always be permitted, whereby a small pilot flame, insufficient for normal heating purposes is maintained even though valve D is closed.

In operation, water flows into the generator A 75 through pipe 12 and is discharged through outlet

13 into the pan 9. When the pan 9 is completely filled it overflows in the form of drops falling from the upper edge of the pan into the annular basin or reservoir 8, and in the form of a thin film flowing down the inclined walls 11 of the pan. Any excess of water in reservoir 8 flows through openings 25 and down the inner surface of inner annular wall 6 into the reservoir 15. Any excess of water in reservoir 15 flows down through air tube 14 and out through pipe 16 and the discharge pipe 26 to the sewer.

Assuming that a partial vacuum exists within the generator A, valve D will be opened to admit fuel gas to the burner 21 and air will be drawn in through supply pipe 16 on account of the lower pressure existing within the generator. The gas and combustion air will be ignited within combustion chamber 22 and through the surrounding walls will heat the water in receptacles 9, 8 and 15. The products of combustion pass out through the openings 24 and 25 and contact directly with the exposed surface of the water in the three containers and also with the water dropping from the pan 9 and with the thin films of water flowing down the outer surfaces of the containers 9 and 8. As the bodies of water in receptacles 9 and 8 are heated, the water will expand thus causing an overflow in contact with the rising products of combustion. The heating medium consisting of the mixed steam and products of combustion passes out through supply pipe 4 to the radiating system. As the pressure is further lowered within generator A, the valve D will be further opened to admit a greater quantity of fuel gas and a proportionately greater flow of combustion air will be drawn into pipe 16. This provides more rapid combustion and a larger flame 23, and consequently increases the rate of steam generation. When the pressure within generator A rises to atmospheric, valve D will be closed to cut off the supply of gas and no more combustion air will be drawn in through inlet pipe 16. The generator will therefore cease to function, although a small pilot flame will be maintained as hereinabove described. It will be noted that this pilot flame is substantially surrounded by the bodies of water always present in the generator so that a large portion of the heat from this pilot will be absorbed by the water. This minimizes the heat loss, and the pre-heated water present in the generator expedites and facilitates the restarting of the normal generating process.

The heating medium passes from supply pipe 4 through risers 42 and inlet valves 43 to the respective radiators or heat emitters B. While only two radiators B have been here shown by way of example it is to be understood that a greater number of radiators can be used. Each inlet valve 43 comprises the usual cut-off valve operated by handle 44, and a metering plate 45 provided with a central orifice 46 is interposed between the valve chamber and the inlet 47 leading to the radiator. The orifice 46 in plate 45 will be properly proportioned to meter the right proportion of heating medium to each radiator depending upon the size, volume and condensing capacity of the radiator. It will be understood that when valve 43 is closed no heating medium at all is admitted to the radiator, but when the valve is opened a restricted flow of heating medium is admitted to the radiator through the orifice plate.

One or more of the valves 43 may be provided with a small opening to permit the outflow of the products of combustion of the pilot-flame even 75

though the valves are closed. This opening insures sufficient draft of air to supply the pilot flame but not sufficient to create a vacuum in the boiler that will operate the diaphragm 5 valve D.

Discharge pipes 48 lead from the respective radiators B to an outlet main 49 leading up to the exhausting mechanism C. This exhausting mechanism comprises a suitable fan or other 10 suction device 50 driven by motor 51 and adapted to draw gases through main 49 and expel them through pipe 52 to the outer atmosphere. The motor 51 is supplied with power through leads 53 and controller 53', and may be manually thrown 15 into or out of operation by the switch indicated diagrammatically at 54, or may be automatically thrown into and out of operation in accordance with changes in the temperature within the building or at predetermined times by means of thermostat 55.

The condensate formed within the radiators B flows out through pipes 48, 49 and 12 and thence back into pan 9 of generator A. An inlet pipe 56 from the outside water supply and controlled by valve 57 leads into pipe 12 whereby the system may be properly filled with water after same has been drained, or additional water may be added when necessary. However, when the system is once properly filled and in operation there will ordinarily be an excess of water in the generator due to water vapors formed in the combustion process, this excess being discharged through pipe 26 as already described.

When exhauster C is in operation it will draw gases through pipes 49 and 48 and create a vacuum in the radiators B. If one or more of the inlet valves 43 are opened, this suction will be transmitted through pipes 42 and 4 to the generator A consequently lowering the pressure in the generator, opening the fuel valve D and drawing in combustion air through pipe 16. The burner will heat the water within the generator producing steam which, together with the products of combustion, is drawn out as a heating medium through supply main 4 and risers 42 and admitted in properly metered proportion through orifice 46 to the radiator. The radiators B will be made comparatively large so that practically all of the steam will be condensed and give out its heat while within the radiators, and such heat as remains within the non-condensable combustion gases will also be utilized for heating purposes while within the radiators. The non-condensable gases are drawn out by the 50 exhausting mechanism C through pipes 48 and 49 and expelled through pipe 52 to the outer air. The condensate formed within the radiators flows down through pipes 48, 49 and 12 into the generator where it is reconverted into steam.

It will now be seen that if an additional inlet valve 43 is opened so as to throw an additional radiator B into service there will be an additional condensing space and an additional drain of heating medium through the supply pipe into this radiator thereby further lowering the pressure within generator A. As already described, this serves to admit an increased supply of fuel and combustion air to the generator thus automatically increasing the rate of generation of the heating medium to care for the increased demand. The system is thus practically automatic, the rate of generation of the heating medium being varied in accordance with the number of radiators thrown into service by operation of the inlet valves 43.

It will now be apparent that the system can only be operated when sub-atmospheric pressures exist in the system, and the generation of the heating medium is controlled automatically by the changes in this sub-atmospheric pressure, which in turn are controlled by the changes in the volume of radiating space put into service.

The system is entirely closed from the atmosphere within the building, and if any leakage occurs it will be into the system due to the lower 10 pressure existing therein, and there will be no escape of combustion gases into the rooms.

One of the principal objections to heating systems heretofore used which utilized the products of combustion as a heating medium has been the 15 corrosive effect of these gases in the piping system and radiators. This corrosive action is largely caused by excess air in the system, when combustion air is supplied under pressure. Since this system operates under a vacuum, excess air 20 is practically eliminated and corrosion is minimized. The inside of all metal parts may also be coated with a corrosion resistor, if desired.

This type of heating system is most efficient since there is very little heat developed in the 25 system that is not radiated or conducted into the building for heating purposes. Practically the only heat losses are in the non-condensable gases which are discharged by the exhausting mechanism C through pipe 52, and these gases have 30 already given up most of their heat while in the radiating system and are at a much lower temperature than the gases ordinarily discharged through the chimney of an ordinary furnace. It will be noted that the excess water discharged through pipe 26 passes out through the air inlet conduit 16 so as to heat the incoming combustion air and thus minimize the heat losses at this point.

It will be noted that this system utilizes only 40 a single pump which functions to maintain the circulation in the system, to exhaust the non-condensable gases from the system, and to supply the fuel and combustion air in proper proportions to the generator.

While a gas-burning furnace has here been shown by way of example, it will be apparent that a burner utilizing oil or solid fuel for combustion purposes could be substituted by making suitable changes in the form of generator and 50 supply connections used.

This heating system is particularly adapted for use in small buildings where a simple and inexpensive system is desirable. This system utilizes 55 a minimum number of parts, which are largely interchangeable, occupy little space, and are easily controlled. It will be understood that the system here shown and described by way of example is merely illustrative, and many changes 60 may be made in the form, number and proportions of the parts used without departing from the broad principles of this invention as set forth in the claims which follow.

We claim:

1. The method of heating consisting in admitting water, combustion air and fuel to an enclosed combustion space, burning the fuel in said space, and maintaining a sub-atmospheric pressure in a radiating space connected with the 70 combustion space whereby the mixed fluid heating medium formed in the combustion space is drawn therefrom and into the radiating space, and a partial vacuum is created in the combustion space, increasing or decreasing governing 75

the rate of fuel supply and the inflow of combustion air from the outer atmosphere in response to an increase or decrease respectively in the degree of vacuum in the combustion space, and 5 varying the volume of the radiating space in which the heating medium is partially condensed and consequently varying the degree of vacuum in the combustion space.

2. The method of heating consisting in burning 10 fuel in the presence of water and thus creating a mixed heating medium in a confined space forming one portion of a circulation system, the system embodying a plurality of spaces from which heat is emitted wherein the steam in the 15 heating medium is condensed thus producing a partial vacuum in the system, exhausting the cooled non-condensable gases from the system, returning the condensate to the combustion space for re-conversion into steam, varying the number 20 of heat emitting spaces in service and thereby varying the degree of partial vacuum thus created in the system, and automatically increasing or decreasing the quantity of heating medium produced in response to an increase or decrease 25 respectively in the degree of vacuum thus produced.

3. The method of heating consisting in burning fuel in the presence of water and thus creating a mixed heating medium consisting of steam and products of combustion in a confined combustion space, circulating the heating medium through a radiating system comprising a plurality of condensing spaces, restricting the inflow of heating medium to each space in accordance 30 with the condensing capacity of the space, condensing the steam in the condensing spaces and withdrawing cooled non-condensable gases from the system thereby maintaining a partial vacuum in the system, varying the number of condensing spaces in service thus varying the pressure 35 in the combustion space, and automatically increasing or decreasing the rate of combustion in accordance with a decrease or increase in pressure respectively in the combustion space.

4. The method of heating consisting in generating 45 a mixed heating medium consisting of steam and gaseous products of combustion in one portion of a closed circulation system, condensing the steam in a remote portion of the circulation system and exhausting the cooled 50 non-condensable gases from the system and thereby creating a partial vacuum in the closed system and causing the circulation therein, and increasing or decreasing the inflow of combustion 55 air and fuel to the generating space in response to an increase or decrease respectively in the degree of vacuum created in the system.

5. The method of heating consisting in generating 60 a mixed heating medium consisting of steam and gaseous products of combustion in one portion of a closed circulation system, condensing the steam in a remote portion of the circulation system and exhausting the cooled non-condensable gases from the system and thereby 65 creating a partial vacuum in the closed system and causing the circulation therein, increasing or decreasing the inflow of combustion air and fuel to the generating space in response to an increase or decrease respectively in the degree 70 of vacuum created in the system, and automatically stopping the exhausting process and hence decreasing the vacuum when a predetermined maximum temperature is reached in the space being heated.

75 6. The method of heating consisting in gener-

ating, by burning fuel in the presence of water, a mixed heating medium consisting of steam and gaseous products of combustion in one enclosed space of a circulation system, causing circulation of this heating medium to another portion of the system wherein the steam is condensed and the non-condensable gases give out some of their heat and exhausting the cooled gases from the system thereby creating a partial vacuum throughout the system and causing the circulation, and returning the condensate to the generating space, the combustion air being drawn into the generating space by the partial vacuum created in the system, and increasing or decreasing the rate of fuel supply in response to an increase or decrease respectively in the degree of vacuum in the generating space.

7. Method of heating which comprises: introducing water into a steam generating and mixing space; causing hot gases of combustion to pass 20 through said space in contact with the water to generate the same into steam, passing the mixture of steam and combustion gases through a heat emitting space, maintaining sub-atmospheric pressure in both spaces by condensing the 25 steam and withdrawing cooled non-condensable gases from said heat emitting space; and increasing or decreasing the rate of introduction of combustion gases to said generating space and starting or stopping the withdrawal of non-condensable 30 gases from the heat emitting space in response to a predetermined decrease or increase respectively in temperature at a determined point.

8. The method of heating consisting in generating 35 a heating medium in an enclosed generating space under a sub-atmospheric pressure which is automatically lowered or raised respectively in response to an increase or decrease in the heat requirements in a space to be heated, 40 the heating medium consisting of mixed steam and products of combustion, and circulating this heating medium through spaces in which the steam is condensed and from which the heat is emitted, the rate of production of the heating medium being regulated by changes in the controlled pressure in the generating space, a lowered pressure increasing the rate of generation and an increased pressure decreasing this 45 rate.

9. The method of heating consisting in burning fuel in an enclosed generating space in the presence of water so as to generate a heating medium consisting of mixed steam and products of combustion, automatically maintaining a sub-atmospheric pressure in the generating space 55 which pressure is raised or lowered respectively in response to a decrease or increase in the heat requirements in a space to be heated, and circulating the heating medium through spaces in 60 which the steam is condensed and from which the heat is emitted, the rate of production of the heating medium being regulated by changes in the controlled pressure in the generating space, a lowered pressure increasing the rate of generation and an increased pressure decreasing this 65 rate.

10. The method of heating consisting in generating 70 in an enclosed generating space under a thermostatically controlled sub-atmospheric pressure a heating medium consisting of mixed steam and products of combustion, and circulating this medium through spaces in which the steam is condensed and from which heat is emitted, the rate of production of the heating 75

- medium being regulated by changes in the controlled pressure in the generating space, a lowered pressure increasing the rate of generation and an increased pressure decreasing this rate.
- 5 11. The method of heating consisting in burning fuel in an enclosed generating space in the presence of water and under a thermostatically controlled sub-atmospheric pressure so as to generate a heating medium consisting of mixed steam and products of combustion, and circulating the heating medium through spaces in which the steam is condensed and from which the heat is emitted, the rate of production of the heating medium being regulated by changes in the controlled pressure in the generating space, a lowered pressure increasing the rate of generation and an increased pressure decreasing this rate.
- 10 12. The method of heating consisting in burning fuel in the presence of water in a closed combustion space to produce a partially condensable heating medium consisting of products of combustion and steam, the combustion space being connected with a condensing space into which the heating medium is introduced, exhausting the cooled non-condensable gases from the condensing space and thereby maintaining a controlled partial vacuum in the condensing and combustion spaces, causing circulation of the heating medium, and producing a suction for drawing combustion air into the combustion space, returning the condensate to the combustion space, and utilizing an increase or decrease in the controlled pressure in the combustion space to automatically decrease or increase the supply of fuel to the combustion space.
- 15 13. The method of heating consisting in burning fuel in the presence of water in a closed combustion space to produce a partially condensable heating medium consisting of products of combustion and steam, the combustion space being connected with a condensing space into which the heating medium is introduced, exhausting the cooled non-condensable gases from the condensing space and thereby maintaining a controlled partial vacuum in the condensing and combustion spaces, causing circulation of the heating medium, and producing a suction for drawing combustion air into the combustion
- space, returning the condensate to the combustion space, thermostatically controlling the sub-atmospheric pressure in the spaces and utilizing an increase or decrease in the controlled pressure in the combustion space to automatically decrease or increase the supply of fuel to the combustion space.
- 20 14. The method of heating consisting in burning fuel in an enclosed generating space under a controlled sub-atmospheric pressure in the presence of water so as to generate a heating medium consisting of mixed steam and products of combustion, circulating this heating medium under sub-atmospheric pressure through spaces in which the steam is condensed and the non-condensable gases are relieved of a portion of their heat, exhausting the non-condensable gases from the condensing spaces thereby maintaining the sub-atmospheric pressure in the generating and condensing spaces, returning the condensate to the generating space and automatically increasing or decreasing the rate of combustion in the generating space in response to an increase or decrease, respectively, of the partial vacuum in the generating space.
- 25 15. The method of heating consisting in maintaining a controlled sub-atmospheric pressure in an enclosed generating space comprising a combustion space and a mixing space, burning fuel in the combustion space and passing the hot combustion gases through the mixing space in contact with exposed water in this space so as to generate a heating medium consisting of mixed steam and products of combustion and circulating this heating medium under sub-atmospheric pressure through spaces in which the steam is condensed and the non-condensable gases are relieved of a portion of their heat, exhausting the cooled non-condensable gases from the condensing spaces thereby maintaining the sub-atmospheric pressure in the spaces and returning the condensate to the mixing space, and stopping or starting the exhausting process in response to temperature changes in the space heated by heat discharged from the condensing spaces.
